UNITED STATES PATENT OFFICE.

WILLIAM TURNBULL, OF STOCKTON, CALIFORNIA, ASSIGNOR TO THE HOLT MANUFACTURING COMPANY, OF STOCKTON, CALIFORNIA, A CORPORATION OF CALIFORNIA.

MULTIPLE-DISK CLUTCH.

1,327,576.

Specification of Letters Patent.

Patented Jan. 6, 1920.

Application filed January 11, 1917. Serial No. 141,772.

To all whom it may concern:

Be it known that I, WILLIAM TURNBULL, a citizen of the United States, residing at Stockton, in the county of San Joaquin and 5 State of California, have invented new and useful Improvements in Multiple-Disk Clutches, of which the following is a specification.

This invention relates to multiple disk 10 clutches; and has for its object to simplify and improve the construction and operation of such devices.

In the present form of the invention, I 15 employ a clamping device, actuated by a toggle joint to increase the pressure on the pressure plate, so that the springs employed in connection therewith may be light enough to be compressed without difficulty by the operator but their effective pressure, or that 20 brought to bear against the disk, will be multiplied several fold by means of the toggle-actuated clamping devices, and the tendency of the pressure plate to move outward, when the clutch members are engaged, 25 will be positively restrained by the toggle mechanism without imparting any strains to the pressure springs.

One form which my invention may assume is exemplified in the following description and illustrated in the accompanying drawings, in which—

Figure 1 shows a side elevation of a clutch embodying my invention.

Fig. 2 shows a sectional view, taken on the 35 line 2—2 of Fig. 1.

Fig. 3 shows a sectional view, taken on the line 3—3 of Fig. 2.

Fig. 4 shows a detail, sectional view of 40 one of the bracket members for the clamping devices on line 4—4 of Fig. 3.

Fig. 5 is a detail perspective view of the 45 annular pressure plate 18.

Fig. 6 is a perspective view of the clutch 50 actuating collar.

Fig. 7 is a perspective view of the flanged 55 collar 22, showing the yokes 28.

The clutch assembled in its present form 60 includes a driving shaft 10, on which is fixed a driving clutch member 11 carrying a set of spaced driving disks 12, secured thereto by keys 13, said disks being preferably of the dry type faced with leather, fiber or similar friction material. The driving clutch member 11 is provided with

an extended hub or shoulder 19. A driven 55 member 14, in the form of a drum, is mounted upon a sleeve 15 carried loosely on the shaft 10 and has disks 16 secured thereto by keys 17, said disks 16 being fitted between the disks 12. An annular plate 18 60 engages the disks at the front of the drum, being supported upon the inner surface of the annular disk carrying flange formed on the member 11.

For actuating the pressure plate, I employ 65 a series of clamping levers 20 pivoted to brackets 21, the latter formed on a flanged collar 22 carried on hub 19 of the driving member. A lug 23, on the clamping lever, near the fulcrum thereof, is adapted to engage 70 the annulus of the pressure plate, when the lever is moved outwardly to force said plate inwardly against the disks. For actuating said clamping levers I connect each with a link 24, pivoted to a clutch actuating 75 collar 26, the latter splined on hub 19 of the driving clutch member. Fixed upon the clutch actuating collar is a series of stud bolts 27, projecting inwardly through an aperture in the end of a yoke 28, which 80 yoke is fixed upon the flanged collar 22. A spring 29 acts between the head 30 of the bolt and the end of the yoke to thrust the bolt inwardly, carrying with it the clutch actuating collar.

As shown in Fig. 4, the flanged collar 22 85 is retained in place by means of stud bolts 31 fixed to the driving clutch member and projecting through bosses on the brackets 21.

When the clutch actuating collar is at its 90 inward limit of movement the links 24 will be at right angles to the axis of the driving shaft, in which position the clamping levers 20 will be moved outwardly into a position parallel with the axis of said shaft and in so moving the lugs 23 will have forced the pressure plate inwardly a sufficient distance to put the driving and driven disks into operative relation. It will be seen that 95 when the clutch is set, the links 24 and clamping levers 20 form a toggle joint for positively retaining the pressure plate in position to hold the driving and driven disks in operative relation and, therefore, the constant strains usually imposed upon the 100 springs are entirely removed at this time.

To release the clutch, the operator pulls

the clutch actuating device outwardly, allowing the links 24 and levers 20 to tend toward a straight line, in doing which the outer ends of the clamping levers 20 will 5 be moved inwardly, thus permitting the pressure plate to release the friction disks. The springs 29 need be of only sufficient force to actuate the clamping levers, through the medium of the shiftable clutch actuating 10 device and the links 24, which, in view of the connections described, require but very little power as compared with the power required to actuate the pressure plate.

Various changes in the construction and 15 arrangement of the several parts herein shown and described may be employed without departing from the spirit of my invention as disclosed in the appended claims.

Having thus described my invention, what 20 I claim and desire to secure by Letters Patent is—

1. A multiple disk clutch including driving and driven members and interposed friction disks, a pressure plate for the disks, 25 an actuating collar for said pressure plate, a plurality of springs acting on said collar at spaced intervals about its circumference, and power increased lever connections between the clutch actuating collar and pressure 30 plate for actuating the latter.

2. A multiple disk clutch including driving and driven members and interposed friction disks, a pressure plate for the disks, a clutch actuating collar spring pressed at 35 spaced intervals about its circumference, power increased lever connections between the clutch actuating collar and pressure plate for actuating the latter, said lever connections comprising clamping levers for the 40 pressure plate, and link connections between

said clamping levers and the clutch actuating collar.

3. A multiple disk clutch including driving and driven members with interposed friction disks, a pressure plate for the disks, 45 a clutch actuating device rotatable with the driving member and shiftable relatively thereto, yoke members carried by the driving clutch member, stud bolts on the clutch actuating device projecting through said yoke members, springs on the stud bolts 50 forcing the clutch actuating device inwardly, and connections between said clutch actuating device and the pressure plate for actuating the latter.

4. A multiple disk clutch including driving and driven members with interposed friction disks, a pressure plate for the disks, a clutch actuating device rotatable with the driving member and shiftable relatively 60 thereto, yoke members carried by the driving clutch member, stud bolts on the clutch actuating device projecting through said yoke members, springs on the stud bolts 65 forcing the clutch actuating device inwardly, and connections between said clutch actuating device and the pressure plate for actuating the latter, said connections including clamping levers pivotally supported by the driving member and engaging the 70 pressure plate, and links connecting said clamping levers with the shiftable clutch actuating device.

In testimony whereof I have hereunto set my hand in the presence of two subscribing 75 witnesses.

WILLIAM TURNBULL.
